UNITED STATES PATENT OFFICE.

JAMES F. LOUCKS, OF CLEVELAND, OHIO, ASSIGNOR TO HOLORIB, INC., OF CLEVELAND, OHIO, A CORPORATION OF OHIO.

CLAMPING DEVICE.

Application filed February 13, 1925. Serial No. 8,894.

This invention relates to clamping devices and, while capable of use in other relations, is peculiarly adapted for the purpose of securing to special joists structural sheet metal units of the general type shown in application No. 686,493 filed jointly by myself and Harry Gillett on January 16, 1924. The general object of the invention is to provide a simple, economical, and efficient means for securing or clamping such sheet metal constructions to joists and particularly to joists of the type that are known to the trade as "bar joists", each such joist comprising a pair of bars suitably secured together to form a unitary structure. Further and more limited objects of the invention will appear hereinafter and will be accomplished and realized in and through the construction and arrangement of parts shown in the drawings, wherein Fig. 1 represents a sectional view through a sheet metal structure, showing the same secured to a joist of the type referred to by means of clamps constructed in accordance with my invention; Fig. 2 a plan view of the joist and of one of the clamps shown in Fig. 1; Fig. 3 a detail in section corresponding to the line 3—3 of Fig. 1; and Fig. 4 a detail in perspective of one of the clamps.

Describing the various parts by reference characters, 1, 1 denote a pair of round bars constituting a joist known to the trade as a "bar joist". As shown herein, the bars 1 are arranged side-by-side, and cooperating with such bars is a metal sheet 3 having hollow ribs projecting downwardly therefrom, one of such ribs being shown at 4 and each of the ribs being triangular in section, with the tops of the ribs substantially closed, whereby the upper surface of the sheet 3 will be substantially continuous or uninterrupted while the bottom of the sheet will be provided with triangular ribs adapted to rest upon the tops of the bar joists. The details of construction of the structural unit and the purposes and advantages thereof are fully set forth in our aforesaid application, the clamping means shown herein being particularly designed for securing sheets or units of this general character to bar joists, on which they are additionally supported by means of the hollow ribs referred to.

Each of the clamping devices is made of sheet metal and comprises generally a channel-shaped member adapted to be slipped

over the bars constituting the joist, with the web or base portion of the channel resting on the tops of the bars of the joist, one lateral edge of the base being provided with an integral post projecting upwardly therefrom and having a tongue adapted to be projected through a metal sheet and secured thereto, there being shoulders interposed between the tongue and the body of the post.

5 denotes the web or base portion of the channeled clamping member and 6 the sides or flanges thereof, the base having the shape in elevation of a flattened U, the distances between the inner faces of the flanges 6 being such as to enable the base member 5 to be slipped downwardly upon the bars 1 with the sides of the flanges 6 engaging the outer sides of the bars. The sides or flanges 6 are substantially at right angles to the main body of the base, being united thereto by curved portions 6^a which conform to the curvature of the upper outer surfaces of the rods 1 which constitute the joist.

Projecting from one of the lateral edges of the web portion 5 is a post 7, the post being shown as having inwardly inclined sides 7^a, there being horizontal shoulders 8 provided at the tops of the sides and a central tongue 9 projecting upwardly from the central portion of the post, the tongue being pointed, as shown at 9^a, to facilitate its application to a metal sheet.

With the parts constructed and arranged as described, each clamping device will be slipped over the bars constituting the bar joist, after which the ends of the flanges 6 will be driven or otherwise bent into engagement with the lower and outer sides of the bars, as shown at 6^a in Fig. 3. The sheets 3 will then be applied to the bar joists and to the clamps and, with a proper punch, will be driven downwardly upon the tongues 9, which will puncture the sheets, after which the tongues will be bent down to lock the sheets against the shoulders 8, as shown in the drawing. In practice, it is preferred to make the height of the posts 7 from the web 5 to the shoulders 8 slightly less than the depth of the ribs 4, making it necessary to spring the sheets downwardly in securing them upon the clamping devices and thus giving a firm hold of the sheets upon the joists.

For convenience of description, the sheets 3 are assumed to be applied to the tops of

the joists, with the clamping members resting on top of the joists and interposed between the same and the lower surfaces of the said sheets; and the terms "upper" and "lower" have been employed in the description and claims, to set forth the relative positions of the parts, but without any intention thereby to limit my invention to a construction wherein the positions of the beams and of the sheets may not be other than those specifically shown and described herein.

Having thus described my invention, what I claim is:

- 15 1. A clamping device for securing a metal sheet in spaced relation to a joist comprising a sheet metal spacing and clamping member having a base adapted to rest upon said joist and sides adapted to receive the 20 sides of the joist and to be bent into engagement with the lower outer surfaces thereof, and a post projecting upwardly from one 25 of the lateral edges of said base, the said post having a tongue at its upper end adapted to be projected through said sheet and a shoulder adapted to be engaged by the sheet when the tongue is so projected therethrough.
- 30 2. A clamping device for securing a metal sheet in spaced relation to a joist comprising a sheet metal spacing and clamping member having a base adapted to rest upon said joist and sides adapted to receive the sides 35 of the joist and to be bent into engagement with the lower outer surfaces thereof, and an integral post projecting upwardly from one 40 of the lateral edges of the portion of the base which rests upon the joist, the said post having a tongue projecting upwardly from the central portion thereof with a shoulder at the base of said tongue, whereby the tongue may be projected through the

sheet and bent downwardly into engagement with the upper surface thereof and the lower surface of the sheet seated upon the 45 said shoulder.

3. A clamping device for securing a metal sheet in spaced relation to a joist having convex sides, the said device comprising a sheet-metal member adapted to be slipped 50 over the said joist with its sides engaging the sides of the joist, the lower ends of the sides being adapted to be bent into engagement with the lower outer surfaces of the 55 joist, there being a post formed with and projecting upwardly from one of the lateral edges of the base, the said post having a tongue adapted to be projected through such metal sheet and a seat at the base of 60 said tongue for the lower surface of the sheet.

4. A clamping device for securing a metal sheet in spaced relation to a joist having convex sides, the said device comprising a 65 U-shaped sheet-metal member adapted to be slipped over the said joist with its base and the upper ends of the sides engaging the top and upper surfaces of the joist sides, the lower ends of the sides of said device being adapted to be bent into engagement with the 70 lower outer surfaces of the joist sides, there being a post formed with and projecting upwardly from one of the lateral edges of the said base, the said post having at its upper end a tongue with a shoulder at the base 75 thereof, whereby the tongue may be projected through such sheet and bent into engagement with the upper surface thereof, forcing the lower surface of the sheet into engagement with said shoulder.

In testimony whereof, I hereunto affix my signature.

JAMES F. LOUCKS.
